UNITED STATES PATENT OFFICE

ROBERT J. PARSONS, OF SCHENECTADY, NEW YORK, ASSIGNOR TO CONSOLIDATED CAR-HEATING COMPANY, OF ALBANY, NEW YORK, A CORPORATION OF NEW YORK

TREADLE-SWITCH

Application filed October 26, 1928. Serial No. 315,248.

My invention relates to a switch that is to be operated by a treadle such as one forming a step leading to and from the platform of a car, whereby the weight of a person on the step will cause the closure and the removal of said weight and reopening of an electric circuit.

For a detailed description of the present form of my invention, reference may be had to the following specification and to the accompanying drawings forming a part thereof, wherein

Fig. 1 is a plan view of my device;

Fig. 2 is a section thereof on line 2—2 of Fig. 1;

Fig. 3 is a section thereof on line 3—3 of Fig. 1;

Fig. 4 is a plan of the switch with the cover thereof lifted;

Figs. 5 and 6 are sections on lines 5—5 and 6—6 respectively of Fig. 4;

Fig. 7 is a section similar to Fig. 6 with the switch-carrier lifted;

Fig. 8 is a plan and

Fig. 9 a vertical section of the treadle-stop.

In the drawings, A, A, A of Fig. 1 represent the four bars of a rectangular frame in which the treadle is set. Underneath is a pan B secured to the bars. C is the treadle-plate which fits in between the end bars A A of said frame and is hinged near its rear edge to the said bars by the bolts a, a. Under the front corners of the plate are two stops D, D, which are seated on the bottom of the aforesaid pan B and screwed thereto by the screws d, d, etc. The details of these stops are shown in Figs. 8 and 9. In those figures d¹ is a disc of rubber or like material with a metal disc d² secured around its periphery to the under side of the rubber disc d¹ by screws, but spaced therefrom at its center to form a pocket in which plays vertically a cross bar d⁴ on the upper end of a standard d³ which is secured to the bottom of pan B by the three screws d, d, d, aforesaid. The said cross bar d⁴ is oblong in shape and a hole having a corresponding shape is formed in the floor of the pocket formed by the under disc d². Thereby, assuming that the standard d³ is in place on the floor of pan B and pro-

jecting upwardly therefrom, the united discs d¹ and d² may be set down over the standard and on the compressed spring d⁶. Then the oblong cross-bar d⁴ of the standard will enter, through the correspondingly shaped opening in the floor of the pocket, into the pocket or cavity between the two discs. If the united discs are then turned 90 degrees around the circular neck of d³ they will be locked to the standard d³ by the oblong cross bar d⁴ which now extends transversely across the oblong opening through which it entered the pocket. The spring d⁶ will also be locked in place between disc d² above and the floor of pan B below. By this arrangement both the up and the down movements of the treadle-plate C will be stopped by the impact of the metal cross bar d⁴ against a rubber abutment which abutment is the disc d¹ for the upward and an underlying rubber washer d⁵ for the downward stop impact. This serves to eliminate the unpleasant sound of metal striking against metal, and also provides a treadle stop in both directions which is independent of the switch that is operated by the treadle-plate.

In Fig. 1 the switch-box E is shown in dotted lines in plan view and in Fig. 2 an end view of it appears in full lines. The box is of sheet metal and is seated on the floor of pan B near the front edge of treadle-plate C. Its cover is hinged to the box at its rear edge and secured at its front edge by a spring clip F. Through the two side plates of the box extends a horizontal shaft G around which, near its middle, is an insulating sleeve g. On each end of the shaft is secured a block H having a short radial lever arm h that rests on top of a switch-actuating spring K seated on the floor of the pan B. The said spring K tends to rotate shaft G in a switch-opening direction. A second block J is mounted loosely on shaft G but at one end is adjustably secured to block H by a bolt j and a slot, and at its opposite end is provided with a roller L which bears against the under side of the treadle-plate C as shown in Fig. 3. By adjusting the angular relation of blocks H and J by means of the bolt and slot connection, the switch-opening spring K keeps the

roller L constantly in contact with the treadle-plate C to prevent chattering and slack in spite of variations in the level of the treadle-plate when elevated due to wear on the rubber of stops D, or other causes. On the aforesaid insulating sleeve g on shaft G and within the switch-box is clamped a member P which may be termed a carrier for the contact piece that makes and breaks the electric circuit. This carrier may be clamped at any appropriate angle with respect to shaft G and will rotate therewith. The electric contact piece is marked R. As shown in Fig. 4 its outer end is forked and serves to connect electrically the two terminals T and Q when it is in its raised position bearing resiliently on the under sides of the respective terminals. The contact piece R is held up against the under side of carrier P by means of a bolt N which passes upwardly through it and the carrier. Under a nut on the end of the bolt is a spring O which seats on the upper side of the carrier. The bolt is loose in the carrier so that the contact piece R can move longitudinally thereon. A pin S projects down from the carrier through a hole in the tail of the contact piece. The operation is indicated at Figs. 5, 6, 7. Not only are the forked ends of the contact piece put into or out of contact with the circuit terminals T and Q but when in contact therewith are also moved transversely with respect to said terminals to scour the surfaces.

In operation the weight of a person stepping on treadle-plate C will depress that plate against the roller L and thereby compress spring K and rotate shaft G and carrier P a slight distance before the plate is arrested by the spring stops D, D. The movement of the carrier tends to compress the spring O which will first draw the contact-member R upwardly into contact with terminals T and Q, thereby closing the electric circuit as shown in Fig. 6. Then the further movement of the carrier will compress spring O to hold the contacts together and because the terminals T and Q limit radial movement of the member R, said member R will be caused to slide forward on the contacts to rub and clean them while pressed against them by spring O. Thus the treadle C has its own movement, limited by the stops which ultimately acts on the contact member R through spring O which has its independent range of movement that is stopped by the contacts T and Q. When the person steps off the treadle-plate the reverse actions take place and the circuit is broken.

What I claim as new and desire to secure by Letters Patent is:

1. The combination with a movable treadle plate and an electric switch operated thereby, of a stop member positioned to be engaged by said treadle plate and movable to conform to the movements thereof, and abutment means

for limiting movement of said stop member, said abutment means including means for deadening impacts of said stop member in both directions of its movement.

2. In combination, a treadle-plate, an electric switch, a shaft for the switch and two radial members on the shaft adjusted with respect to each other, one of said members being engaged by the plate and the other member bearing on a switch-opening spring. 75

3. A treadle operated switch comprising an electrical switch, a spring pressed arm connected with the movable member of said switch and acting to maintain it in a predetermined position, an operating arm connected with the first mentioned arm, and a treadle plate disconnected from said arm but normally bearing thereon, the connection between said arms being adjustable to vary their angular relation, so that engagement of the treadle plate and the operating arm may be maintained to prevent chattering of the parts during operation thereof. 80

4. A treadle operated switch comprising an electrical switch, a rock shaft for actuating the movable member of said switch, a spring pressed arm connected with said rock shaft and movable therewith, said arm acting to maintain said movable contact in a predetermined position, an operating arm connected with the first mentioned arm, and a treadle plate disconnected from said operating arm but normally bearing thereon, the connection between said arms being adjustable to vary the angular relation of said arms, so that engagement of the treadle plate and the operating arm may be maintained to prevent chattering of the parts. 100

5. A treadle operated switch comprising an electrical switch, a rock shaft operatively connected with the movable member of said switch, a spring pressed arm connected with said rock shaft so as to be movable therewith, said spring pressed arm acting to maintain the said movable contact in a predetermined position, an operating arm loosely mounted on said rock shaft, means adjustably connecting said arms so that their relative angularity may be changed, and a treadle plate disconnected from said operating arm but normally bearing thereon, said adjustable connection of said arms serving to maintain contact between the treadle plate and the operating arm to prevent chattering of the parts during operation thereof. 110

6. A treadle operated switch comprising a rock shaft, stationary contacts, a movable contact connected with said rock shaft and mounted to move transversely with respect to the fixed contacts, a spring arm connected with said rock shaft and acting to maintain said movable contact in a predetermined position, an operating arm connected with the first mentioned arm, and a treadle plate disconnected from said operating arm but nor- 125

inally bearing thereon, the connection between said arms being adjustable to vary their angular relation, so that engagement of the treadle plate and the operating arm may
5 be maintained to prevent chattering of the parts during operation thereof.

7. A treadle switch comprising a rock shaft, a stationary electric contact, a carrier on the shaft, a contact piece loosely mounted
10 on the carrier, a spring between said carrier and said contact piece, an operating member on said shaft, and a circuit opening spring also acting on said shaft, said operating member acting at one side against the treadle plate
15 and at the other side against said spring.

Signed at Albany, county of Albany, State of New York, this 23 day of October, 1928.

CERTIFICATE OF CORRECTION.

Patent No. 1,886,497.

November 8, 1932.

ROBERT J. PARSONS.

It is hereby certified that the name of the assignee in the above numbered patent was erroneously described and specified as "Consolidated Car - Heating Company", whereas said name should have been described and specified as "Consolidated Car - Heating Company, Inc.", as shown by the records of assignments in this office; and that the said Letters Patent should be read with this correction therein that the same may conform to the record of the case in the Patent Office.

Signed and sealed this 3rd day of January A. D. 1933.

(Seal)

M. J. Moore,
Acting Commissioner of Patents.
